UNITED STATES PATENT OFFICE.

JAMES H. CLEARWATER, OF WEST NEW YORK, NEW JERSEY.

PIPE-CLEANER.

No. 902,803.

Specification of Letters Patent.

Patented Nov. 3, 1908.

Application filed September 9, 1907. Serial No. 391,925.

To all whom it may concern:

Be it known that I, JAMES H. CLEARWATER, a citizen of the United States of America, and a resident of West New York, county of Hudson, State of New Jersey, have invented certain new and useful Improvements in Pipe-Cleaners, of which the following is a specification, reference being had to the accompanying drawings, forming

10 a part thereof.

My invention relates to improvements in pipe cleaners and comprises a resilient rod or stem provided with a suitable hand piece and a bit at the opposite end thereof, such 15 bit being of peculiar conformation whereby it will most readily hold a cleaning material, and, further, will properly guide itself along the bore of a curved pipe stem.

In order that my invention may be fully 20 understood, I will now proceed to describe an embodiment thereof, having reference to the accompanying drawings illustrating the same, and will then point out the novel features in a claim.

25 In the drawings: Figure 1 is a view in partial side elevation and partial central longitudinal section of a pipe cleaner and shield therefor. Fig. 2 is a view in elevation of the pipe cleaner removed from the shield. 30 Figs. 3 and 4 are detailed views on an enlarged scale of the end of the device at which the bit is located. Fig. 5 is a view in elevation of the pipe cleaner, showing the same as being forced through the stem of a pipe, 35 the pipe being shown in central longitudinal section. Fig. 6 is a view in elevation of a modified form of the device.

The pipe cleaner comprises a stem 10, a hand piece 11 and a bit 12. The stem 10 is 40 preferably composed of a flexible material such as spring steel, so that it may bend readily to conform to the bore of a pipe having a curved stem, yet will return to its normal straight condition when removed therefrom. The hand piece 11 may be of any 45 convenient form, being shown in Figs. 1, 2 and 5 as a cylindrical knob; while in Fig. 6 it is shown as a continuation of the stem 10, and such continuation being bent around and 50 twisted upon itself, as shown at 12* in such figure.

In Figs. 1, 2 and 5 the hand piece is shown as provided with a reduced portion 13 which is screw threaded. Such screw-threaded 55 portion is fitted to a corresponding internally screw-threaded portion 14 in the end

of a shield or casing 15 designed to receive the stem and bit of the cleaner. The cleaner, thus protected by the shield or casing, may readily be carried in the pocket, and in Fig. 60 1 I have shown the said shield 15 as additionally provided with a chuck 16 adapted to receive a lead 17, whereby the said shield or casing may also constitute a lead pencil 65 holder.

The bit 12 comprises a portion thinner in one direction than the stem 10, as is shown in Fig. 4, and wider in the other direction, as is shown in Fig. 3. It is conveniently formed as an integral portion of the stem 70 10 by flattening the end thereof. At its extremity the edges of the widened portion are curved, as at 18, and at the end a recess 19 may be provided if desired.

In using the device a piece of thin tissue 75 paper or fabric is wrapped around the bit 12, and the same is forced through the stem of the pipe in the manner shown in Fig. 5. By attaching the fabric or paper on the end of the bit by a twist in one direction, 80 the same may be readily released by a twist in the opposite direction; thus, after the same has been forced through a pipe in the manner shown in Fig. 5, clear into the bowl thereof, such piece of paper or fabric may 85 be released from the holder by such twist in the opposite direction, and the holder removed, leaving the cleaning material in the bowl from which it may be later ejected.

The peculiar shape of the bit—wider in one 90 direction than the stem—causes it to readily hold the cleaning material, while the curved surfaces 18 not only prevent the cleaner from being forced right through the cleaning material while the device is being passed 95 through the pipe stem, but also serve as

guiding surfaces to properly guide the cleaner along the bore of a curved pipe stem, as is shown in Fig. 5, preventing the cleaner from catching in the walls of the bore, as it might otherwise readily do. The recess 19 is formed for the purpose of retaining a piece of string should it be desired to use a short piece of string as a 100 cleaning material, string being a material which some smokers prefer to use for this purpose. In this case the string is looped over the end of the bit, being received in the recess 19, and is forced through the pipe stem in such manner as will be well understood.

The device above described forms a very 110

simple inexpensive and efficient pipe cleaner, having sufficient rigidity to enable it to be forced through a pipe stem, yet being resilient enough to readily follow the curvature of other than straight stems. As before stated, the shield enables the device to be readily carried about in the pocket without soiling or damaging the clothing, and also without there being any liability of the device itself becoming damaged.

What I claim is:

A pipe cleaner comprising a hand piece,

a resilient stem, and a bit at the end of said stem adapted to receive and retain cleaning material, said bit formed as a continuation of the stem but thinner in one direction and wider in the other than the said stem, said bit curved toward the extremity and provided with a recess at the extremity, substantially as set forth.

JAMES H. CLEARWATER.
